By R. J. McCarthy,
his ATTORNEY:

UNITED STATES PATENT OFFICE.

HENRY R. GUMMER, OF DAYTON, OHIO.

DESIGN FOR A STOVE-BASE.

SPECIFICATION forming part of Design No. 27,268, dated June 29, 1897.

Application filed May 3, 1897. Serial No. 634,972. Term of patent 7 years.

To all whom it may concern:

Be it known that I, HENRY R. GUMMER, a citizen of the United States, residing at Dayton, in the county of Montgomery and State of Ohio, have invented and produced a new and original Design for Stove-Bases, of which the following is a specification, reference being had to the accompanying drawings, forming a part thereof.

Figure 1 is a plan view of the base of an oval stove made in accordance with my design. Fig. 2 is a sectional view taken on the line xx of Fig. 1.

The leading features or characteristics of my design consist in a base for an oval stove, the front half of which has downwardly-extended side walls joined by a floor and a rear upright wall, the said rear upright wall continuing in a horizontal plane rearwardly and forming the floor for the rear half of the base, on a plane above the front floor, and a skirting of ornamental configuration inclosing the upper circumferential edges of the base.

A designates the front portion of the floor, having interior longitudinal ribs a . This floor continues in a rearward integral wall B, that extends upward on a slight incline, and in side walls C, which, together with the rear wall B, provide an inclosure in the front of the stove that constitutes an ash-box. The upper terminals of the walls B and C end in flat surfaces or flanges, as shown in Fig. 1.

The wall B continues rearwardly from its upper terminal in a horizontal plane and constitutes a rearward floor D, which is essentially on a higher plane than the floor A and completes the oval form of the base. The upper surface of the rear floor D is provided with a series of longitudinal depressions b , which allows a greater amount of metal to be used in this section of the floor than is desirable in the front section. The entire floors A and D are surrounded with a marginal channel c and a lateral flange d , which increases in width as it approaches the front, 45 as at d' , and connects the two sides C at the front of the base.

The floor A of the ash-box extends upwardly on an incline, as at A', at the extreme front to provide a suitable entrance for the 50 door E, which it does in conjunction with the sides C and transverse portion d' .

F designates a skirting having the ornamental configuration substantially as shown. This skirting is secured to the rim of the 55 base and conforms to the general contour of the base, which is essentially oval.

What I claim is—

The design for a stove-base as herein described and shown.

HENRY R. GUMMER.
